TRIMMING MACHINE KNIFE GUARD SUPPORTING AND OPERATING MECHANISM

Herbert R. Polleys, New Haven, Conn., assignor to United States Rubber Products, Inc., New York, N. Y., a corporation of Delaware

Application November 13, 1935, Serial No. 49,548

5 Claims. (Cl. 12—51)

This invention relates to a mechanism for supporting and operating a knife guard particularly for use in machines for trimming the upper portion of rubber footwear.

5. In the manufacture of rubber footwear the upper portion is formed with a bead extending around its upper edge and normally a portion of the lining extends beyond this bead which is trimmed away along the outer edge of the bead.

10 In general practice a reciprocating knife is used to sever the extending lining, and a guard is provided for protecting the operator's hands from the knife and is also used to assist the operator in guiding the upper portion of the shoe along

15 in guiding the upper portion of the shoe along a predetermined line underneath the knife. In order to properly guide the shoe upper, the outer edge of the bead contacts with the bottom end of the guide and acts as a stop for guiding the outer edge of the bead in alignment with the outer edge of the shoe upper.

the outer edge of the bead in alignment with the knife or offset therefrom. Heretofore the guard was adjusted in a fixed position in reference to the upper surface of the footwear. As the bottom end of the guard encountered thick portions

of the shoe upper it could not ride over such portions and the cutting operation had to be discontinued at such points. Such thick portions had to be severed manually with a knife before the cutting operation could be continued beyond such points.

30 In accordance with this invention the knife guard is resiliently maintained in contact with the upper surface of the shoe upper or slightly spaced therefrom and when it contacts with such thick portions as may be caused by seams 35 in the shoe upper, it rides over these portions and the cutting operation is not interrupted. For the purpose of raising the guard over excessively thick portions manual means is provided for lifting the guard during the cutting operation.

40 A further advantage of this invention is the provision of means for removing the knife guard from the knife so that it may be easily cleaned and/or adjusted.

45 This invention will be more clearly understood by referring to the following description and the accompanying drawing in which:

Figure 1 is a front end view of a trimming machine showing a mechanism for supporting and operating a knife guard embodying this in-

Figure 2 is a right side view of the mechanism.

Figure 3 is a view of a portion of the mechanism shown in Figure 1 and illustrating the position of the lever 12.

sition of the knife guard when removed from the knife; and

Figure 4 illustrates the reciprocating knife and knife guard in operation upon the shoe upper.

This invention is illustrated in reference to a mechanism for trimming shoe uppers as illustrated in United States Patent No. 1,535,373. As illustrated in Fig. 4 of the drawing, the shoe upper 5 is provided with a bead or binding 6 and excess lining portion 7 which is supported upon a rotatable head 8 having a circumferential knife groove 9 formed therein. The reciprocating knife 10 is secured by means of a screw 11 to the reciprocating bar 12 carried in guides 13, 14 on the head 15. The rotatable head 8 and the reciprocating bar 12 are respectively operated by shafts 16 and 17 driven from the trimming machine 17a shown in outline in dot-and-dash lines in Fig. 1. The knife guard 18 travels along the outer edge of the bead 6 and guides the edge underneath the reciprocating knife 10. The knife guard 18 is secured by screws 19 to a pivotal support 20. The support 20 is mounted on a pin 21 pivotally supported in a yoke 22. The support 20 carrying the knife guard 18 is adapted to move up and down between the arms 23 and 24 of the yoke 22. For this purpose the pin 21 is provided with a head 25 having a circumferential groove 26 formed therein for the reception of the bifurcated ends 27 of a lever 28 which is adapted to actuate the pin and the support 20 carried thereby. The lever 28 is pivoted intermediate its ends on a bolt 30 which is secured in the machine head 15. The upper arm 31 of the lever 28 having the bifurcated ends 27 formed thereon operates the pin 21 up and down and the lower arm 32 of the lever 28 extends downwardly and is connected by a spring 33 to a hook 34 secured to the machine frame 17a. The spring 33 normally pulls the lower arm 32 upwardly and maintains the knife guard 18 in its lowermost position.

A foot-operated pedal 35 is connected to the arm 32 to actuate it in opposition to the spring 33 in order to move the knife guard 18 over the excessively thick portions of the shoe upper when encountered thereby. The pedal 35 is pivoted in a bracket 36 secured to the machine foundation or the frame of the machine. The upper end of the foot pedal 35 is connected to the lower arm 32 of the lever 28 by means of a link 37.

The knife guard support 20 is provided with an enlarged head 38 which extends between the arms 23 and 24 of the yoke 22. The up and down motion of the support 20 may be limited

5 by set screws 39 cooperating with threaded bores in the arms 23 and 24 of the yoke. The screws 39 are retained in any rotated position by means of leaf springs 40 attached to the respective arms 23 and 24 and cooperating with the grooved heads 41 of the set screws 39.

10 The knife guard support 20 being mounted on the pin 21 which is pivotally mounted in the arms 23 and 24 of the yoke 22, and a groove 26 being provided in the head 25 of the pin for the reception of the bifurcated ends 27 of the lever 28, the support 20 may be rotated about the axis of the pin 21 by releasing the retaining clip 42 secured by screw 43 to the guide 13 and moving 15 the clip to the position as shown in Fig. 3. The guard 18 is then rotated in a counterclockwise direction to the position shown. In this position the operator can have free access to the knife blade 10 for cleaning and adjusting it.

20 While the preferred form of this invention has been described herein, it will be understood that changes in the details may be made without departing from the spirit of this invention, and it is intended to protect all the features of the 25 invention that fall within the scope of the appended claims.

Having thus described my invention what I claim and desire to protect by Letters Patent is:

1. In a rubber shoe trimming machine, a mechanism for operating a knife guard, comprising a movable support secured to said guard, means for normally resiliently holding said guard in a predetermined relation with the surface of the work; means for moving said guard in opposition 35 to said resilient holding means and adjustable stops acting upon said support for positively limiting the movement of said guard toward and away from said work.

2. In a shoe trimming machine having a reciprocating knife and a guard therefor, a support 40 for said guard pivoted on an axis substan-

tially parallel to the reciprocating movement of said knife to permit pivotal movement of said guard in reference to said knife, means for normally resiliently holding said guard against the surface of the work, means for moving said guard away from the work in opposition to said resilient holding means, adjustable means for positively limiting the movement of said guard toward and away from the work.

3. In a shoe trimming machine having a reciprocating knife and a guard therefor, a support for said guard pivoted on an axis substantially parallel to the reciprocating movement of said knife, means for retaining said support in its operative pivotal position and releasing said support for pivotal movement in reference to said knife, means for resiliently pressing said support towards the work, foot operated means for moving said support away from said work in opposition to said resilient means, and adjustable means for positively limiting the movement of said support toward and away from said work.

4. In a trimming machine having a knife and a guard therefor, a yoke secured to said machine, a support for said guard pivotally mounted in said yoke, means for resiliently pressing said support towards the work, and adjustable means in said yoke for limiting the movement of said support therein.

5. In a trimming machine having a reciprocating knife and a guard therefor, a movable support for carrying said guard, a yoke secured to said machine, a pivot pin secured to said support and pivoted in said yoke, means for operating said pin up and down with respect to said yoke, means for limiting the up and down movement of said pin, and means for securing said support in its guarding position and for releasing said support for pivotal movement about said pin.

HERBERT R. POLLEYS. 40
